UNITED STATES PATENT OFFICE.

PATRICK C. CONNORS, OF MONTPELIER, INDIANA.

MEANS FOR OPERATING WELLS.

SPECIFICATION forming part of Letters Patent No. 743,249, dated November 3, 1903.

Application filed August 7, 1903. Serial No. 168,663. (No model.)

To all whom it may concern:

Be it known that I, PATRICK C. CONNORS, a citizen of the United States, residing at Montpelier, in the county of Blackford and State 5 of Indiana, have invented certain new and useful Improvements in Means for Operating Wells, of which the following is a specification.

This invention has relation to mechanism 10 chiefly designed for operating a series of wells, thereby economizing in energy, cost of machinery, and maintenance of the same.

The chief intention of the present invention is to simplify the connections whereby 15 movement is transmitted from the source of power to the different machines to be operated and to enhance their durability and facilitate the manipulation thereof.

For a full description of the invention and 20 the merits thereof and also to acquire a knowledge of the details of construction of the means for effecting the result reference is to be had to the following description and drawings hereto attached.

25 While the essential and characteristic features of the invention are susceptible of modification, still the preferred embodiment of the invention is illustrated in the accompanying drawings, in which—

30 Figure 1 is a perspective view of a machine or driving mechanism embodying the invention. Fig. 2 is a detail view of a set of connections between the driver and the machine to be driven, parts of the elements being in 35 section. Fig. 3 is a perspective view of the forked coupling-iron. Fig. 4 is a detail perspective view of the eye-coupling. Fig. 5 is a detail perspective view of the hook-coupling.

40 Corresponding and like parts are referred to in the following description and indicated in all the views of the drawings by the same reference characters.

The driver is indicated at 1 and consists, 45 essentially, of an eccentric ring, annulus, or like part mounted upon the eccentric 2, so as to receive a gyratory movement therefrom which imparts a reciprocating movement to the line of connections employed for 50 transmitting motion from the source of power to the several mechanisms to be operated. The eccentric 2 is secured to the shaft 3,

which in turn is provided with a drive-pulley 4, connected by drive-belt 5 with the pulley 6 on the crank-shaft of the engine 7. The 55 driver 1 is provided with a series of lugs 8, to which the inner ends of the line connections are pivotally secured. The driver may be provided with as many lugs 8 as there are machines to be driven. The bell-crank levers 9 have one member connected by rod 10 to the pump or other mechanism to be operated and the other member connected to the driver by the means forming the subject-matter of this application. 65

The line of connections comprises a forked coupling-iron 11, the eye-coupling 12, and the hook-coupling 13. A rod 14 is connected by a swivel-joint to the coupling members 11 and 13, and a rod 15 has similar connection 70 with the eye-coupling 12 and is pivotally connected to the vertical member of the bell-crank lever 9. The forked coupling-iron 11 is cleft at one end and embraces a lug 8, to which it is pivoted by the pin 16, the stem at 75 the opposite end being provided with a head 17, forming a part of the swivel-joint between the parts 14 and 11. The eye-coupling 12 is provided with a loop or eye at one end, and a stem at the opposite end terminating in a head 18, which forms part of the swivel connection between the parts 12 and 15. The hook 19, pendent from the eye-coupling intermediate of its ends, receives the upper ends of the brace 20, which consists of 80 a rod pivotally connected at its lower end to the framework of the driving mechanism and having an eye at its upper end for engagement with the hook 19. The hook-coupling 13 is provided at one end with a head 21 and 85 at its opposite end with a stub-hook for engagement with the eye of the coupling 12. 90

From the foregoing it will be understood that the several couplings 11, 12, and 13 are of similar construction, one end portion being provided with a head and the opposite end portion with either the fork, eye, or hook, as shown most clearly in the detail views, Figs. 3, 4, and 5. The couplings 12 and 13 may be readily disconnected or coupled, 95 thereby admitting of one or more of the pumps or machines being readily thrown out of action or connected with the source of power, as may be required. When the shaft

3 is rotated, the eccentric 2, keyed thereto, has a corresponding movement imparted thereto which imparts a gyratory or wabbling motion to the eccentric annulus or 5 driver 1 and which motion imparts a reciprocating movement to the various line connections and an oscillatory movement to the respective bell-crank levers connected thereto, whereby the pump or other machinery to 10 be operated is actuated.

Having thus described the invention, what is claimed as new is—

1. In combination with a driver and the part to be driven, a line of connections for 15 transmitting the power from the driver to the driven part, the same comprising a series of similarly-formed couplings, each having a head at one end forming a part of a swivel joint or connection and the respective 20 couplings being provided at the opposite end with a fork, an eye, and a hook, substantially as set forth.

2. In power-transmitting means, the combination of a driver, the part to be driven

and connecting means between them, the 25 same comprising coöperating hook and eye couplings, each provided at one end with a head forming part of a swivel-joint and the eye-coupling being provided intermediate of its end with a hook in a plane at a right angle to the eye, and a brace connected with the hook of said eye-coupling, substantially as described.

3. In combination, a driver, the part to be driven, a forked coupling, coöperating hook 35 and eye couplings, a rod connecting the forked and hook coupling, a second rod connecting the eye-coupling with the part to be driven, and a brace between the eye-coupling and the framework of the machine, sub- 40 substantially as specified.

In testimony whereof I affix my signature in presence of two witnesses.

PATRICK C. CONNORS. [L. S.]
